DESIGN FOR AN OIL BAR

Francis Lawrence Ayres, Chicago, Ill., assignor to Stewart-Warner Corporation, Chicago, Ill., a corporation of Virginia

Application June 16, 1945, Serial No. 120,159

Term of patent 14 years

(Cl. D52—2)

To all whom it may concern:

Be it known that I, Francis Lawrence Ayres, a citizen of the United States and resident of Chicago, in the county of Cook and State of Illinois, have invented a new, original, and ornamental Design for an Oil Bar, of which the following is a specification, reference being had to the accompanying drawing, forming part thereof.

In the drawing:

Fig. 1 is a front perspective view of an oil bar showing my new design; and

Fig. 2 is a rear perspective view thereof on a somewhat reduced scale.

I claim:

The ornamental design for an oil bar, as shown.

FRANCIS LAWRENCE AYRES.
